UNITED STATES PATENT OFFICE.

MARTIN A. WOOD, OF MARSHALL, NORTH CAROLINA.

GARMENT-HANGER.

No. 872,100.

Specification of Letters Patent.

Patented Nov. 26, 1907.

Application filed March 25, 1905. Serial No. 252,021.

To all whom it may concern:

Be it known that I, MARTIN A. WOOD, a citizen of the United States, residing at Marshall, in the county of Madison and State of North Carolina, have invented a new and useful Garment-Hanger; and I do hereby declare the following to be a full, clear, and exact description of the invention, such as will enable others skilled in the art to which it appertains to make and use the same.

The invention relates to a garment hanger and has for its object to improve the construction of garment hangers and to provide a foldable or collapsible hanger adapted to be distended or increased in length to suit the size of the garment to which it is to be applied and capable of being automatically extended in such extended position by the weight of the garment whereby it is adapted to hold a garment in proper position and is retained in engagement with the same.

A further object of the invention is to provide a device of this character which, while being capable of use in connection with various kinds of garments will be especially adapted for holding pants in proper position to preserve the creases thereof.

With these and other objects in view the invention consists in the construction and novel arrangements of parts hereinafter described and shown and particularly pointed out in the appended claims.

In the drawings, forming part of this specification, and in which like numerals of reference designate corresponding parts, Figure 1 is a perspective view of a garment hanger constructed in accordance with this invention. Fig. 2 is a plan view of the same, illustrating the manner of folding the parts. Fig. 3 is a cross section on the line 3—3 of Fig. 2.

Referring to the drawing, 1, 1 designate two similar slidably connected frames or sections each constructed of a single piece of stout wire or similar material and composed of two substantially parallel sides 2 curved longitudinally and connected at their inner ends by transverse portions 3 and terminating at their outer ends in upwardly opening hooks 4 or other suitable button-engaging devices adapted to receive the buttons of a pair of trousers whereby the same are suspended from the hanger. The sides 2 which are slightly diverged at their inner ends are coiled thereat to form eyes 4^a, the eyes of one section slidably receiving the sides of the

other section or frame. The sections or frames are adapted to slide on each other to suit the sides of the garment and also to fold the device.

The transverse portions 3 are connected with a supporting or suspending device 5 by means of links 6 which are provided with eyes 7 and 8. The eyes 7 receive the transverse portion 3 and form hinge joints, and the eyes 8 are linked into an eye 9 of the device 5 which is preferably in the form of a hook and which is adapted to fold flat against the frames or sections when the hanger is collapsed.

The curved frames or sections are adapted to fit a coat or vest which may be supported in the usual manner while a pair of pants is suspended from the ends of the frames or sections. The weight of the garment operates through the links to draw the transverse portions 3 towards each other and automatically extends the frames or sections for maintaining them in engagement with and properly adjusted to the supported garments.

It will be seen that the device is exceedingly simple and inexpensive in construction, that it is adapted to fold into a compact form and that it is automatically extended by suspending it from a hook. Also it will be clear that it is capable of supporting an entire suit of clothes and of holding the same in proper position, and that the weight of the clothes will maintain it in proper engagement with them.

It will be seen from the foregoing that the improved device is composed of two slidably connected yokes or frames each provided at its inner, closed end with eyes for the accommodation of the side members of the other yoke, and said side members being provided with hooks at their outer, free ends for engagement with the buttons of the garments to be suspended. This construction is very simple, useful and efficient.

What I claim is,

In a collapsible and extensible garment hanger, the combination of two yokes or frames, each comprising parallel side members, when collapsed or extended, each side member at one of its ends terminates in coils, each oppositely disposed coil being connected by an arch which spans above the said side members and across the space between the same, said side members being outwardly curved before terminating into the

coils a pair of rods 6 having their lower ends formed into several coils 7, about said arches and provided at their upper ends with eyes or loops adapted to register with one another, a hook having an eye received by the eyes of said rods 6, said side members having their outer free ends provided with hooks 4, as and for the purpose specifically set forth.

In testimony whereof I have hereto affixed my signature, in the presence of two wit- 10
nesses.

MARTIN A. WOOD.
